UNITED STATES PATENT OFFICE.

ROBERT L. SANDERSON, OF NILES, OHIO, ASSIGNOR TO THE BOSTWICK STEEL LATH COMPANY, OF NILES, OHIO, A CORPORATION OF OHIO.

WALL-PLUG.

1,006,290.

Specification of Letters Patent. Patented Oct. 17, 1911.

Application filed February 15, 1911. Serial No. 608,756.

To all whom it may concern:

Be it known that I, ROBERT L. SANDERSON, of Niles, in the county of Trumbull and State of Ohio, have invented certain new and useful Improvements in Wall-Plugs; and I do hereby declare the following to be a full, clear, and exact description of the invention, such as will enable others skilled in the art to which it appertains to make and use the same.

The object of this invention is to provide an extremely simple and highly efficient wall plug, having the coöperating yielding sides so connected that while they will permit a nail to be driven between them they will securely hold it throughout its entire length.

The invention will be hereinafter fully set forth and particularly pointed out in the claim.

20 In the accompanying drawings, Figures 1 and 2 are opposite side views. Fig. 3 is a central longitudinal sectional view. Fig. 4 is a cross sectional view on line 4—4, Fig. 1.

Referring to the drawings, 1 designates a 25 stiff metallic plate which is bent back upon itself along the line 2 and is provided with transversely arranged corrugations 3, the inwardly extending corrugations of the opposite sides abutting against each other. The 30 opposite edges of one side are cut away to form approximately U-shape openings 5, while the corresponding edges of the opposite side have lips 6 struck therefrom by cutting away portions of the metal. These 35 lips are extended through the openings 4 and are bent down against the outer face of the opposite side, and thereby the two sides of the plug are securely fastened together adjacent to the flared ends 7 between which

the nail is designed to be driven. In 40 this way the two sides of the plate are securely held to each other by the two lips struck from one side and overlapping and binding against the other side. The greatest strain occurs at the point of entrance of 45 the nail, and this strain being cared for by the lips which are immediately adjacent the entrance insures the two sides being firmly united without any additional securing means.

The plug may be readily made by suitable dies, one set cutting out the openings in one side and the other set cutting out portions of the metal at the other side to form the lips, which latter, when the plate is bent 50 back upon itself, are readily and easily bent over the side having the cut outs.

I claim as my invention:

As an article of manufacture, a wall plug composed of a plate bent back upon itself 60 and having opposite transverse corrugations, one side of the plate having openings cut in its opposite longitudinal edges and the other side of the plate having lips struck 65 therefrom which are designed to be projected through said openings and bent into engagement with the side having such openings within the plane of the edge of such side, said lips and openings being adjacent to the outer ends of the two sides of the 70 plate.

In testimony whereof, I have signed this specification in the presence of two subscribing witnesses.

ROBERT L. SANDERSON.

Witnesses:

W. G. HURLBERT,
JOHN H. WILSON.
